UNITED STATES PATENT OFFICE.

HENRY P. KRAFT, OF RIDGEWOOD, NEW JERSEY.

COMBINED VALVE-CAP AND PUMP-COUPING.

1,261,405.

Specification of Letters Patent.

Patented Apr. 2, 1918.

Application filed February 28, 1916. Serial No. 80,801.

To all whom it may concern:

Be it known that I, HENRY P. KRAFT, a citizen of the United States of America, residing in Ridgewood, in the county of Bergen and State of New Jersey, have invented 5 certain new and useful Improvements in Combined Valve-Caps and Pump-Couplings, of which the following is a specification.

This invention relates to combined valve 10 caps and pump couplings, and aims to provide certain improvements therein.

In an application filed by M. C. Schweinert January 19, 1916, Serial No. 72,878, there is 15 described and claimed a novel construction of valve cap wherein means are provided for using the cap as an inflating device. The present application relates to a particular construction of this device by which the cost 20 is greatly cheapened and the construction is facilitated.

Referring to the drawings which illustrate one form of the invention,—

Figure 1 is an elevation of the preferred form.

25 Fig. 2 is a similar view taken at right angles to Fig. 1.

Fig. 3 is a vertical section.

Fig. 4 is a horizontal section.

Referring to the drawings let A indicate 30 the cap as a whole which is provided with a recess B adapted to fit over the nipple of a tire valve, the wall C being screw-threaded internally to engage the screw-threads of the nipple. Within the recess B is located a 35 packing D and a backing plate E so that the packing may swivel with relation to the body of the cap.

Passing through the cap preferably at 40 right angles to the axis thereof is formed a bore F which is adapted to receive a tubular adapter G. This tubular adapter carries at one end a screw-thread H which is adapted to fit the interior threads of the valve nipple and at the other end is formed with a screw 45 thread I which is adapted to engage a pump coupling.

It will be observed that the standard valve 50 nipple has an external thread which is engaged by the thread C and an internal thread which is adapted to be engaged by the thread H, and ordinarily one or the other of these threads is used to connect the standard pump coupling with the valve. But certain pump couplings notably those 55 which are made abroad are formed with screw-threads which will practically engage

neither the external nor the internal thread of the valve nipple. Usually such couplings are formed with an internal thread which is adapted to engage a thread such as I which is coarser than the thread H. It is hence necessary in using such couplings on the standard valve that some intermediate coupling device shall be provided and this has usually been fitted to the pump coupling it- 65 self. According to the invention described in the aforesaid application the ordinary valve cap is fitted to act as a coupling but in such construction the cap is turned out of solid metal and the threaded portions corre- 70 sponding to H and I are formed integrally to the body of the cap. This construction is relatively expensive and difficult to manufacture.

By the present invention the tubular 75 adapter G is formed separately from the body of the cap and is afterward inserted in the bore F, thus greatly simplifying and cheapening the product. Means are provided for fastening the tubular adapter G 80 securely in the body of the cap, and I prefer to secure this fastening by continuing the thread I along the tubular adapter until it nearly reaches the thread H. According 85 to this method the bore F is provided with an internal screw-thread, and the tubular adapter is screwed into the body of the cap until it reaches its seat. In order to prevent the tubular adapter from becoming unscrewed it is preferably formed with a 90 groove J best shown in Fig. 4, which groove when the tubular adapter is screwed home lies close to the outer surface of the cap. A stamping or swaging tool is then passed over the projecting threaded part I and 95 forces the metal of the body of the cap into the groove J. It then becomes impossible for the tubular adapter to become unscrewed.

It will be observed that the cap acts as a handle for the tubular adapter G in screwing it into the valve nipple and pump connection, while reciprocally the tubular adapter acts as a handle in screwing on the valve cap. I prefer to provide a screw driver projection such as K at the top of the 105 cap as is common with ordinary caps, such screw driver projection being utilized to manipulate the inside working parts of the valve. When this is done the tubular adapter G acts also as a handle for manipulating the cap during this operation. A packing such as M is usually provided

to make a tight joint with the valve nipple while a tight joint with the pump coupling is customarily secured by a tapered face O which bears against a corresponding seat in the pump coupling.

While I have shown and described one construction of the invention, it will be understood that I do not wish to be limited thereto, since various changes can be made 10 therein without departing from the spirit of the invention.

What I claim is:—

1. A valve cap having means for engaging 15 a tire valve and having a bore through it, and a tubular adapter secured in said bore and having threaded portions to engage respectively such tire valve and a pump coupling not adapted to fit said valve.

2. A valve cap having means for engaging 20 a tire valve and having a bore through it, and a tubular adapter secured in said bore and having threaded portions to engage respectively such tire valve and a pump coupling not adapted to fit said valve, said 25 adapter and cap having interengaging portions to fasten the adapter in the cap.

3. A valve cap having means for engaging 30 a tire valve and having a bore through it, and a tubular adapter secured in said bore and having threaded portions to engage respectively such tire valve and a pump coupling not adapted to fit said valve, said tubular member having a groove, and said cap having a portion lying in said groove to 35 fasten the adapter to the cap.

4. A valve cap having means for engaging 40 a tire valve and having a threaded bore through it, and a tubular adapter screw-threaded to engage said bore, and having at its ends screw-threaded portions to engage respectively such tire valve and a pump coupling not adapted to fit said valve.

5. A valve cap having means for engaging 45 a tire valve and having a threaded bore through it, and a tubular adapter screw-threaded to engage said bore and having at its ends screw-threaded portions to engage respectively such tire valve and a pump coupling not adapted to fit said valve, and said adapter and cap having interengaging portions to prevent rotation of said adapter.

6. A valve cap having means for engaging 55 a tire valve and having a threaded bore through it, and a tubular adapter screw-threaded to engage said bore and having at its ends screw-threaded portions to engage respectively such tire valve and a pump coupling not adapted to fit said valve, and said adapter having a groove, and said 60 cap having a portion engaging said groove to prevent unscrewing of said adapter.

7. A valve cap having a recess adapted 65 to receive the nipple of a tire valve, said recess having screw-threaded walls to engage said nipple, and said cap having a screw driver projection in alinement with said recess, and between said recess and projection having a threaded bore, and a tubular adapter threaded to engage said 70 bore, and having at one end a threaded portion to engage an interior screw-thread on said tire valve, and having at the other end a threaded portion adapted to engage an interior screw-thread on a pump coupling 75 which does not fit such valve.

In witness whereof, I have hereunto signed my name in the presence of two subscribing witnesses.

HENRY P. KRAFT.
